ATTORNEY.

UNITED STATES PATENT OFFICE

ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

ENGINE CONSTRUCTION

Application filed January 30, 1928. Serial No. 250,370.

This invention relates to engine constructions and refers more particularly to internal combustion engines of the sleeve valve type. More particularly my invention relates to 5 air cooled sleeve valve engines and provides an improved built up cylinder construction.

One object of my invention resides in providing a light, strong, cylinder construction particularly adapted for use in airplane engines although not necessarily limited thereto. 10 My construction lends itself to quantity production at relative low cost.

A further feature of my invention resides in the provision of a novel cylinder construction in which the ports cooperating with the sleeve valve ports are constructed and arranged in a novel and improved manner facilitating production of the engine. 15

Referring to the accompanying drawings, 20 Fig. 1 is a sectional elevation view through the engine cylinder, and

Fig. 2 is a sectional view through 2--2 of Fig. 1.

In the drawings, reference characters A and 25 B respectively represent the upper and lower cooperating cylinder members, the lower member B being preferably of steel or metal of similar good wearing characteristics and the upper member A being preferably of a 30 relatively light weight metal such as aluminum alloy affording good heat conductivity. The member B is provided with outwardly projecting cooling fins 10 and has an upwardly extending relatively thin-walled cylinder portion 11 preferably terminating in a 35 chamfered or tapered end 12. The member A also has cooling fins 13 projecting from a central body portion 14, the body portion being cylindrically recessed at 15 to receive

40 the cylinder portion 11. The members A and B are serrated or threaded at 16. A re-entrant cylinder head C is secured by studs 17 to member A and is spaced therewithin to form a sleeve pocket 18 accommodating the 45 movement of one or more sleeve valves 19. As illustrated a single sleeve valve of the well known "Burt-McCollum" type is located within the cylinder members A, B, and surrounding the engine piston 20.

50 The member A is formed with intake and

exhaust chambers 21 and 22 respectively for introduction of fuel mixture to the combustion chamber 23 and for the exhaust gases. The chambers 21 and 22 need not be formed with the cylinder ports since I have formed 55 the intake and exhaust cylinder ports 24 and 25 respectively in the cylinder portion 11. This latter portion being relatively thin walled may be conveniently machined with the ports facilitating the production and 60 lessening the manufacturing expense. The sleeve valve 19 is provided with intake and exhaust ports 26 and 27 respectively cooperating with the cylinder ports 24 and 25 for producing the valving functions of the engine 65 in a well known manner.

In assembling the members A and B I prefer to heat the member A and thread it into position on the member B by reason of threads 16. The member A on cooling will 70 thus be shrunk into position producing an assembly of a permanent character. The chamfered end 12 of the cylinder portion 11 will bite into the body portion 14 of the member A producing a seal joint between the combustion chamber 23 and the chambers 21, 22. The cylinder bore may then be ground to size. 75

While I have illustrated my invention in connection with a single sleeve valve engine of the Burt-McCollum type it is apparent 80 that the teachings of my invention may be utilized in connection with other types of sleeve valve and like engines.

What I claim as my invention is:

1. Cylinder construction for sleeve valve 85 engines comprising in combination, a lower member formed with an upwardly extending cylinder portion provided with intake and exhaust ports, an upper member having a downwardly extending portion surrounding 90 the lower member and secured thereto, said upper member having an annular recess receiving the cylinder portion of the lower member and also having intake and exhaust chambers open to the said cylinder ports, 95 ported sleeve valve means within the cylinder portion, and a cylinder head carried by the upper member depending therewith to provide a sleeve pocket.

2. Cylinder construction for sleeve valve 100

- engines comprising in combination, a lower member formed with an upwardly extending cylinder portion provided with intake and exhaust ports, an upper member having a downwardly extending portion surrounding the lower member and secured thereto, said upper member having an annular recess receiving the cylinder portion of the lower member and also having intake and exhaust chambers open to the said cylinder ports, ported sleeve valve means within the cylinder portion, and a cylinder head carried by the upper member depending therewithin to provide a sleeve pocket, the upper extremity 10 of the cylinder portion terminating in a chamfered portion biting into the annular recess of the upper member.
3. Cylinder construction for sleeve valve engines comprising in combination, a lower member formed with an upwardly extending cylinder portion provided with intake and exhaust ports, an upper member having a downwardly extending portion surrounding the lower member and secured thereto, said upper member having an annular recess receiving the cylinder portion of the lower member and also having intake and exhaust chambers open to the said cylinder ports, ported sleeve valve means within the cylinder portion, and a cylinder head carried by the upper member depending therewithin to provide a sleeve pocket, said upper member being of a relatively light weight metal and said lower member being of a metal having good 25 wearing characteristics.
4. Cylinder construction comprising a cylindrical member provided with intake and exhaust chambers, a cylinder head carried by said cylindrical member and having a portion depending therein and spaced therefrom to form a sleeve pocket, a second member secured to the first said member and having a relatively thin walled cylinder member telescoped within the first member, said second 30 member having intake and exhaust ports opening outwardly to said chambers respectively, and sleeve valve means operable within the second member.
5. Cylinder construction comprising a cylindrical member provided with intake and exhaust chambers, a cylinder head carried by said cylindrical member and having a portion depending therein and spaced therefrom to form a sleeve pocket, a second member secured to the first said member and having a relatively thin walled cylinder member telescoped within the first member, said second 35 member having intake and exhaust ports opening outwardly to said chambers respectively, and sleeve valve means operable within the second member.
6. Cylindner construction comprising a cylindrical member provided with intake and 40 exhaust chambers, a cylinder head carried by said cylindrical member and having a portion depending therein and spaced therefrom to form a sleeve pocket, a second member secured to the first said member and having a relatively thin walled cylinder member telescoped within the first member, said second member having intake and exhaust ports opening outwardly to said chambers respectively, and sleeve valve means operable within the second member.
7. Cylinder construction comprising telescoped cooperating members one of which is relatively thin walled and ported for intake and exhaust, sleeve valve means contacting during its movement with both of said members and for the most part with the said thin walled member, the other of said members having intake and exhaust chambers formed around said intake and exhaust ports, and a cylinder head carried by one of said members.
8. Cylinder construction comprising telescoped cooperating members providing substantially a continuous cylindrical bore one of which is relatively thin walled and ported for intake and exhaust, sleeve valve means contacting for the most part with the said thin walled member, the other of said members having intake and exhaust chambers formed around said intake and exhaust ports, and a cylinder head carried by one of said members and having a portion depending within and spaced from the other of said members, said sleeve valve means operating within the space provided by the cylinder head depending portion.
9. Cylinder construction comprising a member of metal having the characteristics of steel and provided with a relatively thin cylindrical wall ported for intake and exhaust, a second member of metal having the characteristics of aluminum alloy and provided with a portion chambered for intake and exhaust telescoped around the ported portion of the first said member, a cylinder head carried by the second said member, and sleeve valve means operable within the first said member and having a bearing during movement thereof with the second said member.
10. Cylinder construction comprising a member of metal having the characteristics of steel and provided with a relatively thin cylindrical wall ported for intake and exhaust, a second member of metal having the characteristics of aluminum alloy and provided with a portion chambered for intake and exhaust telescoped around the ported portion of the first said member, said members having portions cooperating to provide a substantially continuous cylindrical bore, a cylinder head carried by the second said member and having a portion depending therewithin, said de- 120

pending portion extending below the upper extremity of the first said member.

11. Cylinder construction comprising a member of metal having the characteristics of steel and provided with a relatively thin cylindrical wall ported for intake and exhaust, a second member of metal having the characteristics of aluminum alloy and provided with a portion chambered for intake and exhaust 10 telescopied around the ported portion of the first said member, a cylinder head carried by the second said member, and having a portion depending therewithin, said depending portion extending below the upper extremity of 15 the first said member, and above the tops of the said chambers of the second said member.

12. Cylinder construction comprising an outer member formed with an annular recessed portion and an inner member having a 20 relatively thin walled cylinder portion within said annular recess, said cylinder portion having a chamfered end biting into the annular recessed portion forming a seal joint, sleeve valve means within the inner member, 25 and a cylinder head carried by the outer member.

In witness whereof, I hereunto subscribe my name this 26th day of January, A. D. 1928.
